Patented Apr. 30, 1912.

UNITED STATES PATENT OFFICE.

EDWARD BIGNELL, OF LINCOLN, NEBRASKA.

PILING CONSTRUCTION.

1,024,820.

Specification of Letters Patent.

Patented Apr. 30, 1912.

Application filed July 31, 1911. Serial No. 641,608.

To all whom it may concern:

Be it known that I, EDWARD BIGNELL, a citizen of the United States, residing at Lincoln, in the county of Lancaster and State of Nebraska, have invented certain new and useful Improvements in Piling Construction, of which the following is a specification.

This invention relates to improvements in concrete piling, and has for its object to provide piles constructed of cement or concrete, each being formed to provide a carrier of water under pressure, the moving water and weight of the pile tending to form an excavation, and the water operating as a lubricant to reduce friction and prevent adhesion of soil to the surface while the pile sinks or is being driven into the ground.

The invention broadly includes a pile formed with a main channel or aperture through its longitudinal middle, this aperture having transverse branches opening upon the sides of the pile. It also has reference to certain devices useful in connection therewith to facilitate the sinking or lowering of the pile and for reinforcing the concrete structure.

With these objects in view the invention presents a novel construction, combination and arrangement of parts as described herein and claimed, and as illustrated in the drawing, it being understood that changes in form, size, proportion and minor details may be made within the scope of the claims without departing from the spirit of the invention or sacrificing any of its advantages.

In the drawing, Figure 1 is a side elevation, partly in section, of a cement or concrete pile illustrating one embodiment of my invention. Fig. 2 is a transverse section taken on line *a a* of Fig. 1. Figs. 3 and 4 are enlarged detail views relating to Fig. 1. Fig. 5 is a top plan view of the drill-head, as on line *b b* of Fig. 1. Fig. 6 is a side elevation, partly in section of a pile, being a modified form of and believed to be within the scope of the invention. Fig. 7 is a transverse section taken on line *c c* of Fig. 6. Fig. 8 is a bottom plan view of the pile shown in Fig. 6.

Referring now to the drawing for a more particular description, the improved pile consists principally of an elongated standard, stem or body 7 of cement or other similar

adhesive material, preferably formed rectangular in cross section with a longitudinal aperture 8, and with numerous transverse branches or secondary apertures 9 opening upon the main aperture 8 and upon the sides 60 of the stem.

In order to reinforce the cement body of the pile or stem, a pipe 10 may be employed having comparatively short pipes or branches 11 secured thereto and projecting 65 transversely therefrom, pipe 10 being disposed in the main aperture 8 of the pile with its branches seated in the secondary apertures 9. An aperture 12 may be formed transversely near the upper end of the pile 70 to open upon the main aperture 8, and a conducting pipe 13 may be seated therein, said pipe being connected with pipe 10 and preferably being provided with a controlling valve 14; and water under pressure 75 from any suitable source of supply may be introduced or passed through pipe 13 within pipe 10, and will pass out of the branches 11, the force of the flow of water being subject to the control of valve 14. 80

The construction thus far described would be fully operative and useful without the addition of any further devices, provided the pile is to be sunk or lowered in soft ground or in the sand bars or alluvial 85 deposits of streams where they are frequently employed. Since, by this construction, a discharge is provided at the bottom of the pile, water under pressure will cause an excavation to be made at and below the 90 end of the pile. On account of the weight of the pile it will readily sink into the excavation thus formed; and the water which passes out of the secondary pipes or branches 11 will cause a removal of the soil from the 95 sides of the pile, adhesion of the soil being prevented. As the pile gradually sinks into the excavation thus formed, the water discharged from the end of the pile together with the sand and gravel will move upwardly at the sides of the pile. The construction is of great advantage as compared with ordinary concrete piling for the reason that it may frequently be sunk without the use of a pile driver which often causes 100 breakage of the pile from vibration. Also, it occasionally occurs that piles have to be removed after they have been placed in the ground. On account of suction, and by reason of the adhering soil, the removal of con- 105 110

crete piling has been almost impossible and not practicable. The construction of the pile as above described, however, is such that it may be removed, for the reason that 5 water, when forced to points below the bottom and at the sides of the pile, operates as a lubricant to remove adhesions.

In order that the pile may be lowered or sunk in hard soil a tubular shaft 15 may be 10 provided and disposed within pipe 10 to project below the lower end of the pile, its lower terminal being removably mounted upon the downwardly tapered drill-head 16. Any suitable arrangement of devices may 15 be provided for causing a rotation of the tubular shaft so that the drill-head will form an excavation below the pile, and means will now be described for this purpose. At 17 a wheel is indicated, said wheel 20 being keyed upon the shaft and to be actuated by any suitable power to rotate the shaft. The upper end of the concrete stem or pile may be provided with the supporting head or plate 18 having a depressed part at its middle to form the recess or 25 socket 19. The tubular shaft may have a collar 20 for a seating in this recess, whereby the weight of the shaft will be supported upon the pile.

30 The drill-head is preferably formed as a hollow cone-shaped member, of a diameter somewhat greater than the thickness of the pile, and having at its middle a longitudinal pipe-member 21, and its downwardly convergent wall may be formed with numerous 35 perforations 22. A discharge port within the drill-head is indicated at 23, the same being formed in pipe 21 and a second discharge port 23' is indicated at the terminal 40 of the drill, this being the open end of pipe 21; and the drill-head is preferably provided with ridges or fins 24. Since a considerable weight must be sustained by the drill-head, and to the end that the tubular 45 shaft may be removed after the pile has been placed in the ground, a bearing-head 25 is provided which projects below the concrete body of the pile to support the drill-head. The bearing-head may be provided with a 50 mounting in the lower end of the concrete pile at the time the pile is molded, and may be formed with the annular flange 26; and the drill may have flanges 27 mounted thereon to overlap and engage flange 26. The 55 pipe 21 may have a square recess or socket 28 at its upper end, the lower end of pipe 15 having square walls 29 for engagement with the walls of recess 28, and when these parts are in engagement and shaft 15 is rotated, the shaft will cause the rotation of the drill-head, and when desired, the shaft 60 may be removed from its mounting and disengaged from the drill-head.

Any suitable means may be provided to 65 cause water, under pressure, to pass down-

ward through the rotatable wheel, pipe 15 and the drill-head, from a stationary supply pipe 30, the means herein shown being the usual apertured ball 31 rigidly mounted upon pipe 30, and seated in platform 32 secured to wheel 17, by use of which a communication is provided between supply pipe 30 and pipe 15.

At 33 is indicated a check valve, by means of which a control may be made of the pressure of water which passes within pipe 15. It will be noted that the degrees of water pressure provided for pipes 15 and 10 are under separate control, and this is a desirable feature for the reason that, in 70 operation at the commencement of sinking the pile, water is not passed through pipe 10 and branches 11. Also, when hard or soft soil is encountered, the degree of water pressure under control of valve 33 may be 80 varied.

At 34 is indicated a packing box of usual construction mounted upon cap or head 18, within which the tubular shaft may rotate; it is here employed to prevent leakage from 90 the upper end of pipe 10. That part of the drill-head known as pipe 21 may be considered as a continuation of pipe 15 since they are connected and coöperate as a carrier of water.

In operation, water under pressure will move through apertures 22 of the drill-head as well as through the lower openings of pipe 21; the fins 24 of the drill-head tend to loosen the soil, and, by reason of the construction as described, the pile may generally be lowered into the ground without the use of a pile-driver.

By reason of the construction it will be noted that after the pile has been sunk, pipe 15 and the several devices upon the upper end of the pile may be conveniently removed; and this is a desirable feature, to the end that pipe 10 and its branches may then be filled with cement to form a complete, reinforced pile.

Figs. 6, 7 and 8 illustrate a modified form of the invention, wherein the elongated concrete standard or stem 7' is not reinforced; and no drill, and only one control for water pressure is provided, but in other respects it is substantially the same as already described. The concrete stem 7' is provided with a longitudinal aperture 8' with transverse apertures or branches 9' opening upon aperture 8' and upon the sides of the stem; and it has a tapered lower terminal 16', and a discharge port for the longitudinal aperture opening upon the tapered terminal. Also it has a conducting pipe 13' communicating with aperture 8', said pipe having a controlling valve 14'. In operation, water under pressure may be discharged through the lower end of aperture 8' or through the transverse apertures 9' for the purposes 110 115 120 125 130

already described in connection with pipe 10 and the transverse pipes 11 shown in Fig. 1.

While the number of parts employed in 5 the modified structure are less than those illustrated in Fig. 1, they are substantially identical so far as used, and the modified form is considered to be clearly within the scope of the invention.

10 Having fully described my invention, what I claim and desire to secure by Letters Patent is,—

1. An improvement in piling comprising an elongated upright stem of adhesive material having an outwardly tapered member mounted upon its lower terminal and formed with a longitudinal aperture with transverse branch apertures opening upon its sides; a main tubular member seated in 20 and extending the entire length of the longitudinal aperture; secondary tubes disposed in the branch apertures communicating with the main tubular member; and a member communicating with and adapted 25 to convey a supply of water to said main tubular member near the upper terminal of said main tubular member.

2. An improvement in piling comprising an upright elongated body of adhesive material with a main tubular member disposed longitudinally therein, secondary tubes opening at longitudinal intervals of and upon the sides of said elongated body in communication with said main tubular member; a member communicating with and adapted to convey a supply of water to said main tubular member; a rotatable tubular shaft disposed in said main tubular member and provided with a perforated drill-head; 40 and a tubular member for conducting water in communication with the upper part of said rotatable, tubular shaft.

3. An improvement in piling comprising an upright, elongated body provided with a longitudinal aperture and with transverse apertures opening upon the longitudinal aperture and upon the sides of the elongated body, a conducting pipe mounted upon the elongated body and in communication with the longitudinal aperture thereof; a tubular rotatable shaft disposed within said longitudinal aperture; a cone-shaped drill-head disposed below and supported by the elongated body, said drill- 55 head being coupled with and provided with a discharge pipe in communication with said tubular shaft.

4. A pile provided with a central longi-

tudinal tube with transverse branches for conveying water to be discharged outwardly of its sides; a drill-head disposed outwardly of one of the terminals and supported by the pile; and a rotatable shaft connected with and adapted to rotate the drill-head. 60

5. A pile provided with a longitudinal tube with transverse branches for conveying water to be discharged at longitudinal intervals outwardly of its sides; an apertured drill-head disposed below and supported by the pile; and a rotatable shaft disposed in the tube and mounted upon the drill-head, said shaft being tubular to convey water to said apertured drill-head. 70

6. A pile provided with a longitudinal tube with transverse branches for conveying water to be discharged at longitudinal intervals outwardly of its sides; a hollow, cone-shaped drill-head disposed below and supported by the pile, said drill-head having apertures formed in its tapered wall and provided with a central, apertured discharge pipe; a rotatable tubular shaft disposed in the longitudinal tube of the pile to form a water conduit in communication with the discharge pipe of the drill-head. 85

7. A pile provided with a central, longitudinal tube with transverse branches for conveying water to be discharged outwardly of its sides; a drill-head disposed outwardly of one of the terminals and supported by the pile; and a rotatable shaft disposed in said tube and removably mounted upon said drill-head. 90

8. A pile having a body-portion formed of adhesive material with a longitudinal tube disposed therein having transverse branches for conducting water; a cone-shaped drill-head disposed at one terminal and supported by said body-portion, said drill-head being provided with a discharge pipe; a driving-wheel; a tubular shaft disposed in said tube and mounted at one of its terminals upon said wheel, said tubular shaft having its opposite terminal removably mounted upon the drill-head and forming in combination with said driving-wheel and discharge pipe a connected way for the passage of water. 100

In testimony whereof I have affixed my 110 signature in presence of two witnesses.

EDWARD BIGNELL.
